UNITED STATES PATENT OFFICE

JAMES FRANCIS DUFFY, OF HOLLAND, MICHIGAN, ASSIGNOR TO DUFFY MANUFACTURING COMPANY, OF HOLLAND, MICHIGAN, A CORPORATION OF MICHIGAN

DESIGN FOR AN AUTOMOBILE FLOOR MAT

Application filed July 21, 1930. Serial No. 36,423. Term of patent 14 years.

To all whom it may concern:

Be it known that I, JAMES FRANCIS DUFFY, a citizen of the United States, residing at the city of Holland, in the county of Ottawa and State of Michigan, have invented a new, original, and ornamental Design for Automobile Floor Mat, of which the following is a specification, reference being had to the accompanying drawing, forming a part thereof.

Fig. 1 is a plan view of an automobile floor mat showing my new design, and

Fig. 2 is an enlarged perspective view of a portion of the upper left hand corner of Fig. 1.

I claim:

The ornamental design for an automobile floor mat, as shown.

JAMES FRANCIS DUFFY.
